THREAD DRAG TESTER

William P. Ireland, Jr., Haddon Heights, N. J.

Application July 27, 1950, Serial No. 176,226

6 Claims. (Cl. 73—160)

1

The present invention relates to processes of testing thread for frictional drag and to thread drag testers.

A purpose of the invention is to provide an accurate measure of frictional drag of thread, especially as a basis of determining sewability.

A further purpose is to provide a means for testing the effectiveness of thread lubricants and treating compositions.

A further purpose is to progress thread forwardly at a uniform speed, desirably approximating the maximum thread speed in machine sewing, to press opposed drag surfaces against opposite sides of the moving thread under measured loads and to apply increments of increased load to the drag surfaces desirably until the thread breaks in tension.

A further purpose is to load a circular drag surface against a flat drag anvil with the thread interposed between.

A further purpose is to mount one of the drag surfaces, preferably the circular drag surface, on an arm pivoted back of the drag surfaces in the direction of thread motion.

A further purpose is to load the drag surfaces by a pull rod urged downwardly by a pivoted load rocker which is loaded by a weight.

A further purpose is to move the weight along the load rocker by a chain, and desirably to manipulate the chain from a sprocket shaft below the load rocker pivot.

Further purposes appear in the specification and in the claims.

In the drawings I have chosen to illustrate one only of the numerous embodiments in which my invention may appear, selecting the forms shown from the standpoint of convenience in illustration, satisfactory operation and clear demonstration of the principles involved.

Figure 1 is a side elevation of the machine of the present invention with the front cover removed and part of the weight slider broken away.

Figure 2 is a top plan view of Figure 1.

Figure 3 is an enlarged fragmentary section on the line 3—3 of Figure 2.

Figure 4 is a left hand elevation of Figure 3 omitting the forward winding reel.

Figure 5 is a right end elevation of Figure 2, omitting the rear guide roller.

Figure 6 is a fragmentary sectional plan of Figure 1 on the line 6—6.

Figure 7 is a left end elevation of Figure 6, showing the frame in section.

In the drawings like numerals refer to like parts throughout.

2

Describing in illustration but not in limitation and referring to the drawings, wherever reference is made herein to thread it is intended to include any similar material whether designated as thread, yarn, warp, weft or the like, and whether it consists of fibers, continuous filament or otherwise.

The tests of the character to which the present invention is applicable are believed to find their widest application in connection with thread used for sewing, although it will be understood that they are also of importance in connection with thread used for weaving, knitting and other textile operations.

15 It has been found that the effectiveness of sewing and other thread depends not only upon the tensile strength, but upon the uniformity of properties and especially of cross section, and upon the frictional drag of the thread. Mere

20 tests of tensile strength or of uniformity do not correlate well with performance characteristics in sewing and other operations, and experience indicates that a yarn of lower tensile strength may be more sewable than a yarn of higher

25 tensile strength where the former yarn has lower frictional drag.

The testing of frictional drag of thread is not only important in the determination of the properties of the thread itself, but is also very useful to determine the relative merits of various thread

30 lubricants and other textile treating compositions. Tests of this character can be made in accordance with the present invention by testing the same thread before treatment with a given

35 textile treating composition and then after treatment with different textile treating compositions. The test can also be performed on thread which has been treated by a textile treating composition and from which the textile treating composition has been extracted or otherwise removed.

Existing methods of testing thread do not agree well with practical experience as to the sewability of the thread, and one of the important aspects

45 of the invention is that improved correlation is obtained between actual test results and practical sewability experience with the thread. It is thus possible to purchase thread not only by weight and tensile strength, but by frictional drag which

50 indicates sewability, and it is possible to specify lubrication and other liquid treatments on the basis of the resulting frictional drag and corresponding sewability.

In accordance with the invention, the thread

55 under test is progressed forward at a speed which

is uniform and which is desirably standardized at a value approximating the maximum speed of machine sewing. I have found it desirable to employ a speed of forward progression of 25 yards per minute, which corresponds to a comparatively high sewing speed. It will be understood that other speeds of progression can be used and that any test results reported should include a report of the speed of progression.

In accordance with the invention, the thread, 10 while progressing forwardly at the particular chosen speed, is subjected to lateral pressure between drag surfaces. The drag pressure is increased by increments of load, and the load application desirably continues until failure takes place. As soon as failure occurs, the load is removed and the test is repeated on another length of thread until several readings have been obtained, the average being the result reported.

The drag surfaces preferably consist of a longitudinally extending anvil and a circular or cylindrical surface loaded against this anvil.

The machine is supported and mounted on a box-like base 20, having a top 21, a bottom 22 and side walls 23. The box frame has a back 24 and a removable front 25.

The thread 26 under test is withdrawn from any suitable source, such as a spool 27, and is guided in its path through the machine by a rotatable circumferentially recessed guide roll 28 rotatably supported in a bearing bracket 30 from a block 31 on the top of the frame, and then by a guide finger 32 having a downwardly directed guide notch 33 supported on one of the side arms 34 pivoted at 35 on the block 31. At the forward end, the thread is wound around a take-up reel 36, which turns in a direction to wind up the yarn on a shaft 37 rotated at the predetermined speed by a combined variable speed electric rotor and speed reducer 38, supported on a bracket 40 from the frame.

The arms 34 are cross connected by a spacer 41 interconnected with the arms by screws 42. At the ends forwardly of the pivot 35, the arms 34 mount an upper frictional drag element 43 desirably in the form of a cylinder as best seen in Figure 3, and rigidly mounted to the arms and restrained against rotation. In other words, though the frictional drag element is in the form of a roller, it is not permitted to roll. The frictional drag element 43 is above the thread and cooperates with the lower frictional drag element 44 mounted on the top of block 31 and desirably effectively a straight anvil or plate, which is conveniently beveled at 45 at the approaching and leaving edges to avoid abrasive action. It has been found best to employ smooth hardened steel surfaces for both the drag cylinder and the drag anvil, the surfaces desirably being machined or polished to a smoothness which is at least RMS 25.

Load is applied to the drag cylinder by pull rods 46 pivotally mounted at 47 by clevises 48 at the outer ends of the axis of the drag cylinder 43. The pull rods pass through slots 50 in the top 21 of the frame, and at the lower ends are cross connected by a pivot 51. The pivot 51 makes pivotal connection in an opening 52 of a generally horizontal load rocker 53 which extends on opposite sides of the pivotal connection at 52. The load rocker has an upward extending lug 54 at one side of the pivotal connection 52, which has an opening which engages knife edge pivot 55 supported in brackets 56 de-

pending from the top of the frame. The knife edge pivot 55 thus provides fixed pivotal support for the load rocker.

The load rocker has a generally horizontal track or guideway 57 which receives guide rollers 58 pivotally mounted on a slider 60 which supports a load weight 61. It will be evident that the load weight is on the opposite side of pivotal connection 51 of pull rods 46 from the fixed pivot at knife edge 55.

The slider is suitably manipulated along the rocker interior guideway 57 as by chain 62 connected at one point to the slider at 63 and supported at one end by a driving sprocket 64 and at the other end by an idler sprocket 65, both suitably journaled on the load rocker. The driving sprocket 64 has on the same shaft and suitably on the opposite side of the load rocker, a sprocket 66 which supports one end of an adjusting chain 67. The other end of adjusting chain 67 is supported and turned by sprocket 68 which is on shaft 70 journaled in the adjustment rocker and carrying adjustment nob 71 at the front of the frame. A suitable slot 72, allowing adequate freedom, permits the adjustment shaft to pass through the front 25.

An important aspect of the invention is the placement of adjustment shaft 70 immediately below knife edge pivot 55 in the loaded position so that any hand load applied to nob 71 during adjustment will not create error in the loading of the thread.

The position of the slider along the load rocker at any given time may be observed on a scale 72 to indicate the load, the scale being viewed through any suitable slot or window in the front of the machine. The scale may be calibrated in any desired units such as pounds, kilograms, ounces etc.

In operation the weight is first moved to the right in Figure 1. The thread 26 to be tested is looped around guide roller 28 and then carried through notch 33 of guide 32 and started around the wind-up reel, suitably tying the thread to the reel or engaging it in the notch or opening as well known for starting thread on a spool. The motor and speed reducer 38 are then started to wind up the thread on the reel at the standard speed, and then the first increment of load is applied by moving the weight toward the left in Figure 1. Assuming that no break occurs, successive increments of load are applied while the thread continues to travel between the load elements at the standard or any desired speed. If it is merely desired to determine that the frictional drag properties are low enough for a particular use, it may be sufficient in a particular test simply to load the thread up to a certain percentage above the specification value and determine that it does not break under these conditions. The more usual method of operation is to continue loading until the thread breaks, and then repeat the test several times, in each case recording the load at which the thread breaks in tension. The final results will then usually be averaged in making the report, although the individual results or the maximum deviation may also be reported as an indication of the uniformity of the thread.

It will be evident that the invention provides a very simple, reliable and effective manner of testing the frictional drag of thread.

The invention can be applied with various types of loading mechanism, the weight loading mechanism shown being preferred to spring loading

mechanisms which can be used in the invention because of the increased accuracy.

In view of my invention and disclosure variations and modifications to meet individual whim or particular need will doubtless become evident to others skilled in the art, to obtain all or part of the benefits of my invention without copying the process and structure shown, and I, therefore, claim all such insofar as they fall within the reasonable spirit and scope of my claims.

Having thus described my invention what I claim as new and desire to secure by Letters Patent is:

1. The process of testing thread, which comprises progressing the thread forward at a uniform speed, pressing opposed circular and straight longitudinal surfaces against opposite sides of the moving thread under measured loads, and increasing the load against the thread until it breaks in tension.

2. The process of testing thread, which comprises progressing the thread forward, pressing opposed drag surfaces against opposite sides of the moving thread, and applying increments of increased load to the drag surfaces against the thread until it breaks.

3. In a thread drag tester, means for forwardly progressing thread under test, a friction anvil extending longitudinally along one side of the thread, a pivoted arm having a portion extending in the direction of progression, a curved friction loading element mounted on the arm forward in the direction of progression of the pivot and movable toward and away from the thread and the anvil and means for applying a measured load to the arm.

4. In a thread drag tester, means for forwardly progressing thread under test, a friction anvil extending longitudinally along one side of the thread, a pivoted arm having a portion extending in the direction of progression, a curved friction loading element mounted on the arm forward in the direction of progression of the pivot and movable toward and away from the thread and the anvil, a pull rod pivotally connected to the arm forwardly of the pivot and depending below the arm, a load rocker pivotally mounted below the arm, extending generally horizontally and pivotally connected to the pull rod at one side of the pivot of the load rocker, and a weight movable along the load rocker on the side of the pivotal connection of the pull rod remote from the load rocker pivot.

5. In a thread drag tester, means for forwardly progressing thread under test, a pair of friction drag elements engaging the thread on opposite sides, an arm supporting one of the drag elements, a pivot for the arm back of the drag elements in the direction of thread motion, a pull

rod pivotally connected to the arm forward of its pivot, a load rocker pivotally connected to the pull rod below the drag elements and intermediate the ends of the load rocker, a pivot for the load rocker to one side of the pivotal connection to the pull rod, a track running generally horizontally in the load rocker on the opposite side of the pivotal connection to the pull rod from the load rocker, a weight movable in the track, pivoted sprockets on the load rocker at opposite ends of the track, a chain extending around the sprockets and connected to the weight, and a drive for one of the sprockets.

6. In a thread drag tester, means for progressing the thread under test, a pair of friction drag elements engaging the thread on opposite sides, an arm supporting one of the drag elements, a pivot for the arm back of the drag elements in the direction of thread motion, a pull rod pivotally connected to the arm forward of its pivot, a load rocker pivotally connected to the pull rod below the drag elements and intermediate the ends of the load rocker, a pivot for the load rocker to one side of the pivotal connection to the pull rod, a track running generally horizontally in the load rocker on the opposite side of the pivotal connection to the pull rod from the load rocker, a weight movable in the track, an adjustment shaft positioned rotatably on the load rocker below the load rocker pivot, a sprocket on the adjustment shaft, a sprocket shaft at one end of the track pivotally mounted on the load rocker, two sprockets on the sprocket shaft, a first chain interconnecting the sprocket on the adjusted shaft with one of the sprockets on the sprocket shaft, a sprocket pivotally mounted on the load rocker at the opposite end of the track from the sprocket shaft and a second chain mounted over the second sprocket on the sprocket shaft and the sprocket on the load rocker at the opposite end of the track and interconnected with the weight.

WILLIAM P. IRELAND, JR.
